UNITED STATES PATENT OFFICE.

FRANK WELLS, OF PHILADELPHIA, AND GEORGE E. POTTS, OF POTTSVILLE, PENNSYLVANIA,
ASSIGNORS TO THE POTTS POWDER COMPANY, A CORPORATION OF PENNSYLVANIA.

MEANS FOR DETONATING DYNAMITE AND OTHER EXPLOSIVES.

No. 918,907.

Specification of Letters Patent.

Patented April 20, 1909.

Application filed July 16, 1908. Serial No. 443,776.

To all whom it may concern:

Be it known that we, FRANK WELLS, a resident of Philadelphia, Pennsylvania, and GEORGE E. POTTS, a resident of Pottsville, Pennsylvania, both citizens of the United States of America, have invented certain new and useful Improvements in Means for Detonating Dynamite and other Explosives, of which the following is a specification 10 illustrated by drawings.

The invention is designed primarily as a simple and improved means for detonating cartridges of dynamite or other explosive after the same have been inserted in the bed 15 of coal or other body to be blasted by means of the usual bore hole and suitably tamped. By describing the invention as applicable to coal, its applicability to analogous uses will be readily understood.

20 In the drawings, Figure 1 shows a cross section of the bore hole with the cartridge in place and a blasting barrel inserted in the bore hole and surrounded by the tamping, it being understood that on account of the 25 relatively great length of the bore hole an intermediate portion of the same has been omitted from the view. Fig. 2 shows partly in section the detonating cap and squib secured together. Fig. 3 shows a modification 30 of the combined detonating cap and squib. Fig. 4 is a cross section similar to Fig. 1, to show use with a tapered hole in the tamping instead of the blasting barrel.

In Fig. 1 the cartridge C is shown in place 35 at the inner end of the bore hole in the vein of coal B. At D is the tamping surrounding the blasting barrel F of usual construction which has preferably been drawn back from the cartridge an inch or two at its inner end 40 so that the explosion of the detonating cap will not injure it.

At G (Figs. 1 and 2) is shown a detonating cap in the rear end of which is inserted and secured by cementing at g or otherwise a 45 squib H of sufficient strength and power to insure its being able to carry and drive the cap before it throughout the length of the blasting barrel and into contact with the cartridge before the squib is completely 50 burned and the fire reaches the cap. The squib with the attached cap forms a detonating squib which is placed in the mouth of

the blasting barrel, as shown in Fig. 1, and is then ignited, the squib reacting upon the air is driven through the barrel carrying the 55 detonating cap with it into contact with the cartridge. Upon the explosion of the detonating cap the cartridge is thereby detonated or exploded, as will be well understood.

In Fig. 3 a modified construction of the 60 combined squib and cap is shown in which the cap, which may be the usual construction of cap, is inserted within and held by an outer casing h of the squib H' and may be used in the same way as just described. 65

In Fig. 4 a tapered hole in the tamping, which may be made by a tapering rod, is substituted for the blasting barrel of Fig. 1. The making and use of such tapered holes is, of course, well understood, and the detonating 70 squib may be driven through such hole in the same way as through the blasting barrel.

It will be seen that the invention is of very 75 simple nature and that it obviates the necessity of using a long fixed fuse extending to a detonating cap placed at the cartridge. The squib serves not only to carry fire, but also to force the detonating cap through the tubular opening in the blasting barrel or in the 80 tamping and into contact with the cartridge. The squib is of such proportions that the cap is driven into contact with the cartridge before the squib is completely burned, the continued burning of the squib finally causing 85 the fire to reach the cap, which then detonates and in turn detonates the dynamite.

What we claim and desire to secure by Letters Patent is the following:

1. In combination, an explosive cartridge 90 embedded in the coal or body to be blasted, a passageway leading thereto and a combined detonating cap and squib adapted upon ignition to be driven, carrying the detonating cap with it, to the charge to be exploded. 95

2. In combination as a means for detonating an explosive charge, a detonating cap and a squib carrying the said cap the squib adapted upon ignition to be driven, carrying the detonating cap with it, to the charge to 100 be exploded.

3. A detonating squib comprising a squib proper and a detonating cap secured at the front end thereof, the squib adapted upon ig-

nition to be driven, carrying the detonating cap with it, to the charge to be exploded.

4. A detonating squib comprising a squib proper and a detonating cap which receives 5 and is secured to the forward end of the squib, the squib adapted upon ignition to be driven, carrying the detonating cap with it, to the charge to be exploded.

In testimony whereof we have signed this specification in the presence of two sub- 10 scribing witnesses, July 10, 1908.

FRANK WELLS.
GEORGE E. POTTS.
